(57) **CLAIM**

The ornamental design for a golf club, as shown and described.

DESCRIPTION

FIG. 1 is a bottom rear perspective view of a golf club;

FIG. 2 is a left side elevational view thereof;

FIG. 3 is a right side elevational view thereof;

FIG. 4 is a front elevational view thereof;

FIG. 5 is a bottom plan view thereof;

FIG. 6 is a rear elevational view thereof; and,

FIG. 7 is a rear perspective view thereof.

The broken line showing of portions of the golf club is for illustrative purposes only and forms no part of the claimed design.

1 Claim, 7 Drawing Sheets
